UNITED STATES PATENT OFFICE.

WILLIAM G. COX, OF CLEVELAND, OHIO.

SPRING FENDER OR BUMPER.

Application filed April 20, 1923. Serial No. 633,445.

To all whom it may concern:

Be it known that I, WILLIAM G. Cox, a citizen of the United States, residing at Cleveland, in the county of Cuyahoga and State of Ohio, have invented certain new and useful Improvements in a Spring Fender or Bumper, of which the following is a specification.

My general object is to provide a simple spring fender made of front and rear strips or bands of spring metal arranged parallelly in spring bracing and backing relation and adapted to be secured transversely of and to the frame or platform of a vehicle, whereby efficient protection will be given against hard blows or shocks and violent contact with a body will be yieldingly resisted and absorbent.

A more specific object is to provide a pair of spring striking members and complementary brace springs capable of acting either jointly or independently in cushioning a blow or shock. In the accompanying drawing, Fig. 1 is a top view of my improved fender mounted upon one end of a vehicle or car. Fig. 2 is a front elevation of the fender and car. Fig. 3 is a front elevation of the brace springs or bar without the front flexible buffer spring bands, rails or bars. Fig. 4 is an enlarged cross section of the fender on line 4-4 of Fig. 1.

I am aware that it is an old expedient in fenders to use a single flat flexible strip or band of metal as a yielding striking portion, and to support this striking strip or band intermediate its ends by resilient strips of spring metal placed horizontally at the rear thereof. The present device is predicated on that known structure, but differs specifically therefrom in that I use a pair of complementary striking members or impact strips 2 and 3, respectively, made of flat spring metal, and support these two strips edge to edge in spaced vertical relation in the same vertical plane to provide a relatively wide striking area the full length of the fender. These striking strips may be arched more or less their full length, or made straight or nearly straight at their middle and curved at their ends, and the extremities of each strip may be rounded by curling them into closed eyes 4 corresponding to hinge eyes to permit these ends to be pivotally connected together, if desired, or to be pivotally connected to additional supporting parts or posts on the car, platform or frame.

This latter mode of supporting a spring striking strip is not shown inasmuch as it is not claimed herein as new. Instead, I employ two rear supporting bands or bars, 5 and 6, respectively, made of flat strips of spring metal, which have corresponding straight intermediate portions bearing against each other and riveted or bolted together. Each rear band or bar is bent forwardly at its opposite ends to provide diverging spring arms adapted to be riveted, bolted or clamped to the striking members or strips 2 and 3, which as hereinbefore stated are mounted one above the other. Therefore, the spring arms 7 and 8 of the bracing and supporting strips 5 and 6, respectively, are offset vertically to bring their extremities 9 to the same horizontal plane as said strips, the rear supporting strip 5 being made relatively longer than bracing strips 6 and having its ends or arms 7 offset or projected upwardly, and the second strip 6 having its end arms 8 offset downwardly. In this way rear bar 5 serves to support the upper striking rail or strip 2 with spring bracing effect, and the other rear strip or bar 6 supports the lower impact rail or strip 3 independently of the upper rail and also in a yielding bracing manner. If desired, the upper and lower striking rails may be connected together by clamping plates or members 10, either at the middle or elsewhere between their ends.

Any suitable means may be used to attach this protecting spring fender or bumper device to the vehicle frame, but one simple and practical way is to bolt separate clamping brackets 11 to the projecting extensions 12 of the side bars 14 of the frame or platform of the vehicle, substantially as shown in Figs. 1 and 4. The clamping brackets 11 may engage the longer bar 5, or in relatively narrow vehicle frames the clamping brackets may be arranged to grip and hold both bars 5 and 6.

What I claim, is:

1. A flexible fender or bumper for a vehicle, comprising a pair of striking members made of spring band metal, and a pair of brace springs secured together intermediate their ends and having offset extremities engaging the opposite ends of said striking members.

2. A spring fender or bumper for a vehicle, comprising a pair of flexible metal striking bands and separate brace springs

- for said bands secured to each other and adapted to support each band for independent yielding effect.
3. A spring fender or bumper for a vehicle frame or platform comprising a pair of spring striking bands, and a pair of brace springs having diverging end portions supporting said bands parallelly at different elevations.
- 10 4. A spring fender or bumper, comprising a pair of spring-metal bands adapted to provide complementary striking members, and separate spring bracing strips for said members having diverging spring arms offset vertically to support said striking members parallelly one above the other in a common striking plane.
- 15 5. A spring fender or bumper, comprising a pair of complementary spring-metal bands, and separate bracing strips secured together between their ends and having diverging spring arms offset vertically in opposite directions and engaged with said bands.
- 20 6. A spring fender or bumper, comprising a pair of complementary spring-metal striking members, and a pair of supporting strips of different length having spring extremities adapted to support said striking members separately at different elevations with independent yielding effect.
- 25 7. A spring fender or bumper, comprising parallel striking bands of spring-metal, and parallel connected strips of spring-metal having reversely-extending extremities supporting said bands independently one above the other.
- 30 8. A spring fender or bumper, comprising complementary striking bands of spring-metal, and a separate bracing and supporting strip for each band, said strips having parallel intermediate connected portions and forwardly-extending end portions and also offset vertically at their opposite ends to engage said bands, one of said strips being relatively longer than the other to permit attachment of the fender to a vehicle frame.

In testimony whereof I affix my signature hereto.

WILLIAM G. COX.

Witness:

Geo. E. KRICKE.
